UNITED STATES PATENT OFFICE.

FRED D. GRIGGS, OF SPRINGFIELD, MASSACHUSETTS.

DESIGN FOR A SIGNBOARD OR ARTICLE OF SIMILAR NATURE.

Application filed July 12, 1926. Serial No. 18,328. Term of patent 14 years.

To all whom it may concern:

Be it known that I, FRED D. GRIGGS, a citizen of the United States, residing at Springfield, in the county of Hampden and State of Massachusetts, have invented a new, original, and ornamental Design for Signboard or Article of Similar Nature, of which the following is a specification, reference being had to the accompanying drawing, forming a part thereof.

The figure is a perspective view of a signboard or article of similar nature showing my new design.

The cross sectioning indicates a combination of contrasting colors.

I claim—

The ornamental design for a signboard or article of similar nature as shown and described.

FRED D. GRIGGS.
